(57) **CLAIM**

The ornamental design for a fishing lure mold set, as shown and described.

DESCRIPTION

FIG. 1 is a perspective top front right view of a fishing lure mold set, showing a first mold half and a second mold half, showing my new design;

FIG. 2 is a perspective top rear left view thereof;

FIG. 3 is a top plan view of the fishing lure mold set placed side-by-side;

FIG. 4 is a bottom plan view of the fishing lure mold set placed side-by-side;

FIG. 5 is a right elevation view thereof;

FIG. 6 is a left elevation view thereof;

FIG. 7 is a front elevation view thereof; and,

FIG. 8 is a rear elevation plan view thereof.

The broken lines show portions of a fishing lure mold set that form no part of the claimed design.
